(57) **CLAIM**

The ornamental design for collection tool, as shown and described.

DESCRIPTION

FIG. 1 is a perspective view of the collection tool.
FIG. 2 is a front view of the collection tool.
FIG. 3 is a rear view of the collection tool.
FIG. 4 is a top plan view of the collection tool.
FIG. 5 is a bottom plan view of the collection tool.
FIG. 6 is a left side view of the collection tool (a right side view of the Invention appears symmetrical with the left side view of the Invention).
FIG. 7 is a vertical sectional view of the Invention along line 7-7 of FIG. 2.
FIG. 8 is a horizontal sectional view of the Invention along line 8-8 of FIG. 2; and,
FIG. 9 is a horizontal sectional view of the Invention along line 9-9 of FIG. 2.
